(57) **CLAIM**

The ornamental design for a display screen or portion thereof with a graphical user interface, as shown and described.

DESCRIPTION

The FIGURE is a front view of a display screen or portion thereof with a graphical user interface showing our new design.

The even length dashed broken lines are for environmental purposes only and form no part of the claimed design.

The uneven length dash-dot broken lines of the display screen represent an unclaimed boundary line and form no part of the claimed design.

The text, "HR," "STEP," "ECG," "BP," "PPG," "GSR," "BIO-Z," "ACCL," and "HR", and position of said text, is part of the claimed design.
